By R. C. Wright, atty.

UNITED STATES PATENT OFFICE.

JOSEPH L. CHAPMAN, OF HADDONFIELD, NEW JERSEY, ASSIGNOR TO THE WATSON & McDANIEL COMPANY, OF PHILADELPHIA, PENNSYLVANIA.

EJECTOR.

SPECIFICATION forming part of Letters Patent No. 636,953, dated November 14, 1899.

Application filed September 5, 1899. Serial No. 729,450. (No model.)

To all whom it may concern:

Be it known that I, JOSEPH L. CHAPMAN, a citizen of the United States, residing at Haddonfield, in the county of Camden and State 5 of New Jersey, have invented certain new and useful Improvements in Ejectors; and I do declare the following to be a full, clear, and exact description of the invention, such as will enable others skilled in the art to which it applies 10 to make and use the same, reference being had to the accompanying drawings, and to the figures of reference marked thereon, which form a part of this specification.

The object of my invention is to construct 15 a fluid-ejector of fixed parts to lift and force by means of multiple tubes within a cone and of varying length in order to present multiple forcing aperatures within and in parallel lines to the inner diameter of the cone to eject the 20 atmospheric pressure therefrom, the tubes being increased in number as the cone is increased in diameter and their orifices forming increased means to eject the air from the cone in ratio to its increased capacity for holding 25 air-pressure, so that by positive expulsion of the air in multiple jets as the cone enlarges a nearly perfect vacuum shall be formed and a constant and rapid flow of fluid be introduced into and forced from the cone and at a minimum 30 of friction of the fluid, owing to the successive impulses exerted thereon and at different points during its passage. My ejector may be used to hasten the flow in heating-pipes, and thereby increase the circulation 35 therein, as well as for lifting and forcing liquids.

I attain the objects of my invention by the mechanism illustrated in the accompanying drawings, in which—

40 Figure 1 is an elevation. Fig. 2 is a vertical central section. Fig. 3 is an end view of the forcing-tubes. Fig. 4 is a side elevation of the forcing-tubes. Fig. 5 is an end view of a modification. Fig. 6 is a side view of a 45 modification.

Similar figures of reference indicate similar parts throughout the views.

The body of my ejector is of circular form— 50 in part 1 parallel-sided and in part 2 conical or tapered. At the outer end of part 1 is flange 3, which is screw-threaded on its interior

4. At the lower part of 1 is a neck 5, having a hexagonal termination 6, which is screw-threaded at 7, and into it is screwed lifting or suction pipe 8, which communicates to the 55 body of fluid to be operated upon, transferred, or forced. The outer end of part 2 terminates in a hexagon 9, which is interiorly screw-threaded at 10 and into which is screwed delivery-pipe 11. It will be readily understood 60 that I could secure the lifting or suction and delivery pipes by coupling-nuts instead of in the manner shown, and this I do in large-sized ejectors. Screwed into thread 4 and abutting flange 3 is a cap 12, preferably of hexagonal 65 shape on its exterior and tapped with a screw-thread 13, into which is screwed fluid-pressure pipe 14. Within the cap is formed a chamber 15, a head 16 being its inner end. At the center of the head 16 is inserted a forcing² 70 tube 17, which communicates with chamber 15 and projects through the interior of part 1 and extends into the interior of conical part 2 to near its smaller end. Surrounding tube 17 are other forcing-tubes 18, also inserted 75 into and through head 16 and extending through the interior of part 1 and into the interior of conical part 2, parallel to the central tube 17, but to a less extent than tube 17, their outer or delivery ends stopping at line 80 A B, which is parallel to the interior surface of the conical part 2, represented by line C D. (See Fig. 4.) Surrounding forcing-tubes 17 85 18 are forcing-tubes 19, parallel to tubes 17 18 and also inserted into and through head 16, passing within body 1 to line A B (see Fig. 4) and just beyond opening 20 of neck 5, which communicates with the lifting or suction pipe 8.

The number of forcing-tubes to be employed in an ejector will depend upon the diameter and capacity of the ejector and the service in which it is designed to be employed, and I may also vary their relative lengths from that which I have shown, as such modification is sometimes necessary to meet the demands of varying service requirements.

In Figs. 5 and 6 I show a modification in which the central tube 17^a and all the others are secured to head 16^a, and all in parallel 100 lines, the tube 17^a being the longest and each surrounding tube being shortened a gradual

succession of less length, as see Fig. 6 and tubes 21 22 23 24 25 26. When pipe 14 is coupled to the forcing pressure, pipe 8 coupled to the liquid storage to be ejected, lifted, 5 or transferred, and delivery-pipe 11 connected to the place of discharge, then the valve or stop cock connected to pipe 14 being opened pressure will be admitted to chamber 15 and forced through force-pipes 10 17 18 19 and in parallel jets against as many different parts of the interior of conical part 2 as there are pipes whose orifices are presented in line to project against the coned surface, and as the force is distributed and multiplied 15 upon the surface and also diffused so thoroughly through the fluid or atmosphere contained therein the act of expelling it is quick and certain, the action is steady and powerful, and it accomplishes its work with a minimum amount of friction.

I claim—

1. In an ejector, a body having an interior partly cylindrical or parallel-sided and partly coned or tapered, connection from the body 25 to a fluid-supply and to a delivery-pipe, a fluid-pressure inlet to the body, a chamber thereto connected, and leading from the chamber to and within the coned or tapered body part, multiple forcing tubes or pipes of 30 various lengths in parallel lines and discharging against the interior walls of the coned or tapered body part.

2. In an ejector, a body part partly cylindrical and partly coned having a pressure-inlet, a lifting or supply inlet and a delivery-outlet, pipes connected thereto, a chamber in connection with the pressure-inlet and leading therefrom, to and within the coned body part, multiple forcing-tubes of different lengths

grouped in parallel alignment around a central forcing-tube longer than the groups of surrounding tubes.

3. In an ejector, a body part partly cylindrical and partly coned having an entrance and an exit for fluid-flowing, a pressure-entrance opposite the fluid-exit, multiple parallel forcing-tubes of various lengths, opening at one end to the fluid-pressure, and at the opposite end discharging within and against the cone part and toward the fluid-exit.

4. In an ejector, a body part partly cylindrical and partly coned having fluid entrance and exit orifices, and a fluid-pressure entrance having connected therewith multiple parallel forcing-tubes, in groups of different lengths and entering the coned body part at different distances, the longest being at the center and each successive group being shorter than the group which it surrounds, encircles or incloses and each group exterior to the central tube discharging against the interior wall of the coned body part, their orifices being parallel to the coned interior.

5. In an ejector, a body part partly cylindrical and partly coned and means to connect thereto pipes for fluid inflow and outflow, means to introduce fluid-pressure, and connected thereto and discharging within the coned body part and discharging against its coned interior part, multiple parallel forcing-tubes, each tube being of a different length.

In testimony whereof I affix my signature in presence of two witnesses.

JOSEPH L. CHAPMAN.
